LOOSE LEAF RING BINDER

Herbert S. Chase, Woodmere, N. Y., assignor to Bernard Cahn Co., Inc., New York, N. Y.

Application June 19, 1957, Serial No. 46,642

Term of patent 7 years

(Cl. D87—5)

Figure 1 is a front elevational view of a loose leaf ring binder showing my new design in closed position;

Figure 2 is a rear elevational view;

Figure 3 is a side elevational view;

Figure 4 is a view similar to Figure 1 showing the top flap section in open position; and

Figure 5 is a plan view thereof in completely opened position.

I claim:

The ornamental design for a loose leaf ring binder, substantially as shown.
